(57) **CLAIM**

The ornamental design for a wheel loader, as shown and described.

DESCRIPTION

FIG. 1 is a front, top and right side perspective view of a wheel loader according to the design;

FIG. 2 is a rear, top and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is an enlarged view of the portion shown in BOX 8 in FIG. 1; and,

FIG. 9 is an enlarged view of the portion shown in BOX 9 in FIG. 6.

The box labelled as 8 in FIG. 1 and the box labelled as 9 in FIG. 6 are shown in broken lines and form no part of the claimed design.

1 Claim, 8 Drawing Sheets
